DENTURE CLEANER

Robert R. Harrison, Elyria, Ohio, assignor to The General Industries Company, Elyria, Ohio, a corporation of Ohio

Filed Oct. 9, 1964, Ser. No. 82,111

Term of patent 14 years

(Cl. D49—1)

FIG. 1 is a perspective view of the denture cleaner of my design;

FIG. 2 is a side elevational view of the denture cleaner of FIG. 1;

FIG. 3 is a top plan view of the denture cleaner of FIG. 1;

FIG. 4 is a front elevational view of the said denture cleaner;

FIG. 5 is a rear elevational view of the same; and

FIG. 6 is an enlarged fragmentary cross-sectional view, taken through the ribbed, circular portion thereof.

I claim:

The ornamental design for a denture cleaner, as shown.
